UNITED STATES PATENT OFFICE.

NATHANIEL D. ALLEN, OF SAN FRANCISCO, CALIFORNIA.

SHOE.

1,171,689.

Specification of Letters Patent. Patented Feb. 15, 1916.

Application filed May 21, 1915. Serial No. 29,622.

To all whom it may concern:

Be it known that I, NATHANIEL D. ALLEN, a citizen of the United States, residing at San Francisco, in the county of San Francisco and State of California, have invented new and useful Improvements in Shoes, of which the following is a specification.

This invention relates to certain novel and useful improvements in shoes.

10 In carrying out the present invention it is my purpose to provide a shoe which may be slipped on and off quickly and conveniently, which will fit the foot nicely and comfortably when worn, which will retain 15 its shape and which may be quickly and conveniently fastened.

It is also my purpose to provide a shoe wherein the fastening devices may be rapidly and conveniently manipulated to fasten 20 and unfasten the shoe.

With the above recited objects in view, and others of a like nature, the invention consists in the construction, combination and arrangement of parts set forth in and 25 falling within the scope of the appended claims.

In the accompanying drawing:—Figure 1 is a perspective view of the shoe constructed in accordance with my present invention. Fig. 2 is a rear elevation of the shoe showing the parts opened. Fig. 3 is a similar view showing the shoe closed. Fig. 4 is a fragmentary vertical sectional view through the shoe. Fig. 5 is a transverse 35 sectional view therethrough. Fig. 6 is a collective view showing the fastening device removed from the shoe and in perspective.

Referring now to the drawings in detail A designates a shoe comprising a vamp 1, 40 and upper 3, having a reinforcing band 2 extending around its counter portion.

In accordance with my present invention, the upper 3 is slit as at 4 at the rear of the shoe and such slit extends from the heel seat to the top end of the upper. The reinforcing band 2 extending around the counterportion of the shoe is cut out as at 5 from the top of such band to the heel seat to expose the slit in the upper. The counterportion of the upper at the slit therein is secured to the reinforcing band 2 as at 6, while fastened to one end edge of the slit portion of the upper is a fly 7 adapted to overlap the upper at the other side of the slit portion. The companion members of fastening devices or clasps are secured

to the inner surface of the fly 7 and the outer surface of that portion of the upper which the fly overlaps, respectively.

In the present instance each fastening device comprises male and female members 8 and 9 respectively, and the female member is carried by the upper while the male member is secured to the fly. The male member embodies a hollow rivet-like body 60 embedded in the fly having one end offset to secure the same to the fly, and the remaining end formed with a tongue 11 overlying the adjacent end of the body. The female member is identically formed, but 65 in this case the outer end of the tongue 11 is bent inwardly against the adjacent edge of the body as at 12 so that a space 13 is formed between the tongue and the adjacent edge of the body that will receive the 70 tongue of the male member, when the members are connected together in clasped or fastener formation.

In the actual use of the fasteners, the offset ends of the male members carried 80 by the fly 7 are preferably colored to correspond with the color of the fly, and the hollow bodies of such members may be filled with some suitable material.

Secured to the counter 2 at lower end of 85 the slit therein is a tongue 14 whereby the shoe may be easily and conveniently drawn onto the foot of the wearer.

It will be seen that I have provided a shoe 90 wherein the use of buttons, laces and analogous fastening devices is eliminated, while the shoe may be readily and quickly slipped onto the foot of the wearer and removed from such foot, and wherein the fastening devices will hold the fly securely fastened.

While I have herein shown and described 95 one particular form of my invention, by way of illustration, I wish it to be understood that I do not limit or confine myself to the precise details of construction herein described and delineated, as modification and variation may be made within the scope 100 of the claims without departing from the spirit of the invention.

What is claimed is:—

1. A shoe comprising an upper and a reinforcing member therefor extending around the counter portion of the upper, the upper being slit centrally of its rear portion from the top to the heel seat and the reinforcing member being cut out at the center 110 of the counter portion from the top to the

- heel seat to expose the slit in the upper, and a fly secured to one edge of the slit portion of said upper and adapted to overlap the upper at the other side of the slit therein.
- 5 2. A shoe comprising an upper and a reinforcing member therefor extending around the counter portion of the upper, the upper being slit centrally of its rear portion from the top to the heel seat and the reinforcing member being cut out at the center of the counter portion from the top to the heel seat to expose the slit in the upper, a fly secured to one edge of the slit portion of said upper and adapted to overlap the upper at the other side of the slit therein, and a tongue having one end secured to the counter portion of said upper at the lower end of the slit therein to facilitate the application of the shoe to the foot.
- 10 3. A shoe comprising an upper and a reinforcing member therefor extending around the counter portion of the upper, the upper being slit centrally of its rear portion from the top to the heel seat and the reinforcing member being cut out at the center of the counter portion from the top to the heel seat to expose the slit in the upper, a tongue having one end secured to the counter portion of the upper at the lower end of the slit therein to facilitate the application of the shoe to the foot, and means for fastening the upper about the foot at the slit therein.
- 15 4. A shoe comprising an upper and a reinforcing member therefor extending around the counter portion of the upper, the upper being slit centrally of its rear portion from the top to the heel seat and the reinforcing member being cut out at the center of the counter portion from the top to the heel seat to expose the slit in the upper, a tongue having one end secured to the counter portion of the upper at the lower end of the slit therein to facilitate the application of the shoe to the foot, and means for fastening the upper about the foot at the slit therein.

to one edge of the slit portion of said upper and adapted to overlap the upper at the other side of the slit therein, and fastening devices having the members thereof carried by the inner surface of said fly and the outer surface of that portion of the upper which the fly overlaps, respectively.

30 35 40 45

4. A shoe comprising an upper and a reinforcing member therefor extending around the counter portion of the upper, the upper being slit centrally of its rear portion from the top to the heel seat and the reinforcing member being cut out at the center of the counter portion from the top to the heel seat to expose the slit in the upper, a tongue having one end secured to the counter portion of the upper at the lower end of the slit therein to facilitate the application of the shoe to the foot, and means for fastening the upper about the foot at the slit therein.

In testimony whereof I affix my signature in presence of two witnesses.

NATHANIEL D. ALLEN.
